US00D936670S

(12) **United States Design Patent** (10) **Patent No.:** **US D936,670 S**
Amini et al. (45) **Date of Patent:** **** Nov. 23, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mani Amini**, San Jose, CA (US);
Chanaka Karunamuni, Cupertino, CA (US)

(73) Assignee: **Apple Inc.**, Cupertino, CA (US)

(**) Term: **15 Years**

(21) Appl. No.: **29/740,324**

(22) Filed: **Jul. 2, 2020**

Related U.S. Application Data

(63) Continuation of application No. 29/662,909, filed on Sep. 10, 2018, now Pat. No. Des. 889,484, which is a continuation of application No. 29/606,394, filed on Jun. 5, 2017, now Pat. No. Des. 831,039.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet
